CLAIM

We claim the ornamental design for a megaphone for playground, as shown and described.

DESCRIPTION

FIG. 1 is a front view of a megaphone for playground, showing our new design;

FIG. 2 is a rear view thereof;

FIG. 3 is a left-side view thereof;

FIG. 4 is a right-side view thereof;

FIG. 5 is a top view thereof;

FIG. 6 is a bottom view thereof; and,

FIG. 7 is a perspective view thereof.

The broken lines in the figures illustrate the portions of the megaphone for playground and form no part of the claimed design.
